United States Patent Office

Des. 190,976
Patented July 25, 1961

190,976

PHOTOGRAPHIC CAMERA

Ernest P. Taubes, Rochester, N.Y., assignor to Photo Devices, Inc., Rochester, N.Y., and Ideax Corporation, New York, N.Y., New York corporations

Filed Feb. 4, 1960, Ser. No. 59,267

Term of patent 14 years

(Cl. D61--1)

FIG. 1 is a bottom view of a photographic camera, showing my new design;

FIG. 2 is a front elevational view of the same;

FIG. 3 is a top plan view of the same;

FIG. 4 is a rear elevational view of the same;

FIG. 5 is a right-hand side elevational view of the same; and

FIG. 6 is a left-hand side elevational view of the same, looking in the direction of the arrows shown in FIG. 2.

I claim:

The ornamental design for a photographic camera, substantially as shown.
